No. 626,582.

Patented June 6, 1899.

A. WHISLER.

TOOL FOR INSERTING VALVE STEMS IN PNEUMATIC TIRES.

(Application filed June 27, 1898.)

(No Model.)

UNITED STATES PATENT OFFICE.

ALBERT WHISLER, OF GREENTOWN, INDIANA.

TOOL FOR INSERTING VALVE-STEMS IN PNEUMATIC TIRES.

SPECIFICATION forming part of Letters Patent No. 626,582, dated June 6, 1899.

Application filed June 27, 1898. Serial No. 684,614. (No model.)

To all whom it may concern:

Be it known that I, ALBERT WHISLER, a citizen of the United States, residing at Greentown, in the county of Howard and State of Indiana, have invented a new and useful Tool for Inserting Valve-Stems into Pneumatic Tires, of which the following is a specification.

The object of the present invention is to provide a simple and useful tool or implement for inserting metal stems for inflation-valves or the like into pneumatic tires or other hollow rubber or fiber tubing.

The invention consists, essentially, in providing a holder for the valve-stem and a plunger adapted to engage the stem and force the latter into the opening provided therefor in the tire.

Other objects and advantages of the device will be hereinafter more fully described, shown in the drawings, and particularly pointed out in the claims.

The drawings hereto annexed and the description thereof show and set forth the device as applied in use upon a bicycle-tire; but it will of course be understood that the device is capable of inserting similar parts into elastic tubing of any character.

In the drawings, Figure 1 is a plan view of my invention applied to a section of a bicycle-tire and holding a valve-stem in the initial position for insertion. Fig. 2 is a side elevation showing the valve-stem inserted in the tire. Fig. 3 is a longitudinal sectional view of the implement. Fig. 4 is a detail perspective view of the casing and fingers. Fig. 5 is a transverse sectional view on the line $x-x$ of Fig. 2.

Corresponding parts in the several figures are denoted by like characters of reference.

Referring to the accompanying drawings, the tool comprises a holder consisting of a hollow casing 1, having fingers 2 and 3, provided at one end thereof, and a plunger 4, adapted to be inserted at the other end of the casing. The casing is preferably oblong or elliptical in cross-section, so as to provide a convenient hand-grasp for the operation of the device, and the finger 2 is preferably formed as an integral portion thereof. The other fingers 3 are each pivoted to the opposite side of the casing, as at 5, so as to be

swung in the plane of the casing and spread the fingers apart. Each of these fingers is reduced in width, as at 6, for a suitable length 55 of the outer ends thereof, and their extremities are bent or formed into outwardly-extending flanges 7. The integral finger 2 is also formed with such a flange 7. By the disposition of the fingers upon opposite sides of the 60 casing the flanges 7 will extend in opposite directions upon the inside of the tire and serve to hold the device thereon.

The plunger 4 comprises a stem 8, having a head or handle 9 provided at one end and 65 a shank 10 at the other end thereof. The stem is of a size and shape to fit easily within the casing and be guided therein during the operation of the device. The shank preferably tapers toward its end, and a concave 70 notch or seat 11 is formed therein. The plunger may be formed of a single piece or, as shown, with the stem 8, a hollow tube, and the shank 10, connected to one end, and the handle 9, fitted to the other end thereof. The 75 shank should always be of metal to prevent wear or breakage; but the handle may be of wood or other material, as desired.

In the operation of the device the valve-stem 12 is placed between the fingers, as 80 shown in Fig. 1, its head 13 seated therebetween, with the finger 2 extending diametrically across the top and the fingers 3 across the under side thereof and embracing the stem, the body of which extends at approximately 85 right angles thereto. The free ends of the fingers are now placed in the opening, the reduced portion thereof allowing the same to come close together for this purpose. The plunger is then placed in the casing, with the 90 edge of the head 13 seated within the notch 11 in the end of the shank 10. With the device thus assembled the casing is grasped in one hand, with the thumb thereof steadyng the valve and with the other hand pressing 95 upon the handle 9, whereby the plunger forces the stem against the tire, thus spreading the fingers 3 apart by reason of their pivotal connection with the casing and stretching the opening to receive the head of 100 the valve-stem. When the valve-stem has been forced against the tire, a fulcrum-point is obtained at one side of the head, whereby the latter is turned and forced edgewise into

the opening in the tire by continued pressure of the plunger (see Fig. 2) and the valve-stem assumes its proper position, with its head within the tire and its shank protruding from the opening and being received alongside of the shank of the plunger and between the reduced portions of the pivoted fingers 3. The device can then be easily removed by pulling the same from the tire.

10. It will be observed that as the valve-stem is forced against the tire it spreads the pivoted fingers apart and stretches the walls of the valve-stem opening, so as to more easily receive the head of the stem, and that the 15 flanges 7 overlap the inner edges of the opening and prevent the tool from pulling away from the tire until the valve-stem is in place, when the tool may be easily removed.

A tool constructed in accordance with the 20 present invention will provide an exceedingly simple and useful device for placing valve-stems and the like in position without damaging the opening in the tire.

Changes in the form, proportion, and minor 25 details may be made without departing from the spirit and scope or sacrificing any of the advantages thereof, and therefore I do not wish to be understood as limiting myself to the precise construction and arrangement as 30 herein set forth.

Having thus described the invention, what I claim, and desire to secure by Letters Patent, is:

1. A device of the character described, comprising a holder for supporting the valve-stem at approximately right angles thereto, and a plunger adapted to engage with the stem and force the head thereof edgewise into and through the valve-stem opening of the 40 tire, substantially as set forth.

2. A device of the character described, comprising a hollow casing, fingers provided upon the casing forming a holder for supporting the valve-stem at approximately right angles 45 thereto, and a plunger arranged within the casing and adapted to engage and force the head of the valve-stem edgewise into the opening of the tire, substantially as and for the purpose set forth.

3. A device of the character described, comprising a holder adapted to hold the valve-stem by the head thereof with the body of the stem at approximately right angles to the holder, and a plunger adapted to engage the 55 head edgewise of the stem and force the head into and through the valve-stem opening of the tire, substantially as set forth.

4. A device of the character described, comprising a hollow casing, fingers provided upon 60 one end of the casing, some of the fingers being pivoted forming a holder for supporting the valve-stem at approximately right angles thereto, and a plunger adapted to engage with and force the stem into the opening, substantially as set forth.

5. A device of the character described, comprising a hollow casing, fingers provided upon

one end of the casing, the fingers upon one side thereof being fixed and the fingers upon the other side thereof being pivoted to the 70 casing, said pivoted fingers receiving the valve-stem therebetween, and a plunger carried by the casing and adapted to extend between the fingers and engage the valve-stem, substantially as and for the purpose set forth. 75

6. A device of the character described, comprising a hollow casing having a stationary finger at one end and a pair of fingers pivoted to the same end of the casing and upon the opposite side thereof, the pivoted fingers 80 being cut away upon their opposing inner edges and adapted to receive the valve-stem therebetween with its head between the stationary finger and the pivoted fingers, and a plunger arranged within the casing and between the fingers and adapted to engage the head of the valve-stem, substantially as and for the purpose set forth. 85

7. A device of the character described, comprising a holder having fingers adapted to hold 90 the valve-stem therebetween, each of the fingers being provided with an outwardly-extending flange, and a plunger carried by the holder and adapted to engage the valve-stem, substantially as set forth. 95

8. A device of the character described, comprising a holder having fingers adapted to receive the head of the valve-stem therebetween, and a plunger carried by the holder, said plunger being provided with a concaved seat 100 or notch in one end thereof, which is adapted to engage with the edge of the head of the valve-stem, substantially as set forth.

9. A device of the character described, comprising a hollow casing having means for holding the valve-stem at approximately right angles thereto, and a plunger arranged within the casing, said plunger consisting of a stem having a shank at one end adapted to engage the valve-stem and an operating head or handle at the other end thereof whereby the head of the valve-stem may be inserted edgewise into and through the valve-stem opening, substantially as set forth. 110

10. A device of the character described, comprising a holder for the valve-stem and a plunger, the holder having movable fingers which are adapted to support the valve-stem at approximately right angles thereto, and to be inserted in the valve-stem opening of the 115 tire and stretch said opening during the operation of the plunger whereby the head of the stem may be inserted edgewise into and through the valve-stem opening, substantially as set forth. 120

11. In a device of the class described, the combination with the holder for the valve-stem to hold the stem at approximately right angles to the holder and in position for insertion, of means for forcing the head of the 130 stem edgewise from the holder into the valve-stem opening, substantially as described.

12. In a device of the class described, the combination with the holder for supporting

the valve-stem at approximately right angles thereto and adapted to be inserted into the valve-stem opening and expand the same, of means for forcing the head of the stem edge-wise from the holder into the opening, substantially as described.

5 In testimony that I claim the foregoing as

my own I have hereto affixed my signature in the presence of two witnesses.

ALBERT WHISLER.
